UNITED STATES PATENT OFFICE.

LLOYD HAMILL, OF OLATHE, KANSAS.

MAGAZINE-FEED MATCH-BOX.

No. 878,059.

Specification of Letters Patent.

Patented Feb. 4, 1908.

Application filed July 23, 1906. Serial No. 327,340.

To all whom it may concern:

Be it known that I, LLOYD HAMILL, a citizen of the United States, residing at Olathe, in the county of Johnson and State of 5 Kansas, have invented certain new and useful Improvements in Magazine-Feed Match-Boxes, of which the following is a specification.

This invention relates to magazine-feed 10 match boxes, and my object is to produce means whereby an ordinary box of the type in which matches are purchased, may be transformed or converted into a magazine-feed match box and into a receptacle to receive burned matches.

A further object is to produce a magazine-feed match box of simple and cheap construction.

To these ends the invention consists in 20 certain novel and peculiar features of construction and organization as hereinafter described and claimed; and in order that it may be fully understood reference is to be had to the accompanying drawing, in which—

25 Figure 1, is a perspective view of a magazine-feed match box embodying my invention. Fig. 2, is a central vertical transverse section of the same. Fig. 3, is a top plan view of the box member filled with matches 30 and provided with a match-retaining strip of slightly modified form from that commonly used in match boxes. Fig. 4, is a vertical transverse section on the line IV—IV of Fig. 1.

35 In the said drawing, 1 indicates the usual box portion of a match box and 2 the sliding tubular cover therefor. 3 indicates an extension of one of the end walls of the box portion, and 4 wings at the sides of extension 40 3, said wings in length being about equal to the depth of the box portion and provided with diagonal slots 5, extending from their upper or front corners toward the hinge edge of extension 3.

45 When the box is closed the extension 3 and its wings occupy substantially the positions shown in dotted lines Fig. 2, that is to say the extension stands parallel with the top wall of the box portion and the wings by 50 preference fit between the side walls of the box portion and the ends of the matches therein, the sliding cover fitting against the outer side or face of said extension. If desired the parts may be arranged in all respects as explained except that the wings 45 may be folded against the outer sides of the

box portion so as to lie between the same and the side portions of the sliding cover—the first-named arrangement however being preferred.

60 To transform or convert the match box into a magazine-feed box, the box is held horizontally—to prevent matches spilling—and then the sliding cover is partially withdrawn. The extension 3 and its wings are 65 then swung to the position shown in Fig. 2 so as to dispose slots 5 in the vertical plane of the front side of the sliding cover, the latter being then slid further on the box so as to enter said slots and thus retain the extension 70 and wings in the position shown. The box is then disposed vertically and a number of the matches will feed by gravity through the opening formed between the open side of the box and the lower end of the corresponding 75 side of the cover. As thus arranged the match box can be set up on end on any suitable support, and from it matches can be removed as desired from the trough formed by the extension and its wings. In the ad- 80 justment described of the box portion and the cover, an upper chamber 7 is provided into which the burned matches may be deposited. If desired a hole 8 may be made in the bottom of the cover and box portion to 85 be hooked upon a headed projection such as a nail 9 driven into a wall or other support.

In Figs. 3 and 4, I show a modified construction, that is to say, I provide the usual strip employed to retain the matches in the 90 box in case the latter is opened carelessly, with a tongue and from said strip equipped with a tongue in conjunction with the box portion and cover I provide a trough of the character described.

95 In Fig. 3, 10 indicates the body portion of the usual retaining strip referred to, provided with a lateral extension 11, the ends 13 of the strip 10 being provided with the diagonal slots 14 corresponding in form and arrangement to slots 5. This modified type of retaining strip is placed upon the matches with the ends 13 tucked down between the end walls of the box portion and the matches in the usual manner as shown in Fig. 3. To 100 produce a magazine-feed match box, the cover is removed or withdrawn sufficiently to permit strip 10 to be removed from the box. The extension 11 is then slipped between one end of the box portion and the 105 matches therein as shown in Fig. 4. The strip is then bent along the junction of the 110

body portion 10 and the extension 11, so that the former shall project upwardly and outwardly, the ends 13 being then bent toward each other on dotted lines 12 and 5 then preferably slipped between the side portions of the body portion and the matches therein as indicated in Fig. 4 until slots 14 occupy the vertical plane of the front wall of the slide cover. The cover is then slipped 10 further on the body portion and into said slots to lock or secure the parts in the position described. The weight of the major portion of the matches is upon the extension 11 and the interlocked connection between 15 the front wall of the cover and the slots prevents the matches supported mainly by portion 10, from bending the latter downward and spilling upon the floor.

While the use of thin cardboard or stiff 20 paper is preferable to produce the trough it will be understood of course that in the type of construction wherein the part forming the same is detachable from the box as in Figs. 3 and 4, tin, aluminium, or any equivalent 25 thereof may be employed and may be distributed with or independently of the match boxes—that is may be sold directly to the consumer.

From the above description it will be apparent that I have produced a magazine-feed 30 match box possessing the features of advantage enumerated as desirable and I wish it to be understood that I do not desire to be restricted to the exact details of construction 35 shown and described as obvious modifications will occur to one skilled in the art.

Having thus described the invention what

I claim as new and desire to secure by Letters-Patent, is:

1. A magazine-feed match box, comprising a box portion, parts to form a trough at one end of the same, comprising a body portion to project upwardly and forwardly from the lower front edge of the box portion, and wings to project upwardly and rearwardly 45 from the sides of said body portion and fit against the sides of the box portion, and provided with slots, and a sliding tubular cover to envelop the major portion of the box portion and to enter said slots. 50

2. A magazine-feed match box, comprising a box portion, an attachment comprising a part extending upwardly and forwardly from the lower front edge of the box portion when the latter is disposed vertically, a part 55 projecting from the lower edge of said upwardly and forwardly arranged portion into the box portion and resting on the lower end thereof, and parts or wings projecting upwardly and rearwardly from the sides of said 60 upwardly and forwardly extending portion and fitting against the sides of the box portion and provided with slots, and a tubular cover for the box portion, withdrawn to uncover the lower end of the same, and having 65 the lower edge of its front wall engaging said slots to assist in holding wings and the parts from which they project, in position.

In testimony whereof I affix my signature, in the presence of two witnesses.

LLOYD HAMILL.
